UNITED STATES PATENT OFFICE.

WILLIAM C. HIERING, OF NEWARK, NEW JERSEY, ASSIGNOR TO J. E. MERGOTT CO., OF NEWARK, NEW JERSEY, A CORPORATION OF DELAWARE.

DESIGN FOR A COMBINED CIGAR HOLDER AND ASH RECEPTACLE.

Application filed January 22, 1926. Serial No. 16,214. Term of patent 14 years.

To all whom it may concern:

Be it known that I, WILLIAM C. HIERING, a citizen of the United States, residing in the city of Newark, in the county of Essex and State of New Jersey, have invented a new, original, and ornamental Design for Combined Cigar Holder and Ash Receptacle, of which the following is a specification, reference being had to the accompanying drawing, forming a part thereof.

In the drawing,

Figure 1 represents a plan view of a combined cigar holder and ash receptacle, showing my new design,

Figure 2 represents a side elevation, and
Figure 3 represents an under plan view of the same.

I claim:

The ornamental design for a combined cigar holder and ash receptacle, as shown.

WILLIAM C. HIERING.
